ALARM

Nathan M. Levy, Baltimore, Md.

Application June 22, 1936, Serial No. 86,654

12 Claims. (Cl. 116—100)

This invention relates to alarm devices and has particular reference to installations of this kind adapted for protection of homes, banks, offices, stores, barns, storage houses and other buildings and their contents against burglary, robbery and fire.

Among the objects of this invention is the provision of a simple, durable and mechanically actuated alarm which is adapted to produce 10 characteristic warning noises or sounds either by the opening of a door, movement of a window, movement of a window shade, pressure upon a string connected with the alarm or the rise in temperature to and above a predetermined point 15 of the air or atmosphere immediately surrounding the alarm.

More specifically, it is an object of this invention to provide a novel trigger or tripping mechanism whereby the sound-producing parts 20 of the alarm are automatically actuated to indicate burglary, robbery or fire.

A still further object of this invention is the provision of a novel trigger or tripping mechanism for automatically actuating the sound-producing parts of the alarm, said trigger mechanism automatically assuming a given position relative to a door when the door is closing, so that, when in such position, it will be actuated by the door when the door is opened a predetermined amount, the tripping mechanism being disposed to be set in non-actuating position when the door is opened a sufficient amount to permit the insertion of the hand or arm of a person but less than the predetermined amount necessary to actuate this tripping mechanism.

Other, further and more specific objects of this invention will become readily apparent to persons skilled in the art from a consideration of the following description when taken in conjunction 40 with the accompanying drawings wherein:

Fig. 1 is an interior view of a portion of a room showing the use of my alarm device in position for actuation by a door or by movement of window shades or by bearing upon a string when giving a robber alarm or by a rise of temperature of the atmosphere to a predetermined point as in the case of fire.

Fig. 2 is a top plan view of the alarm device, with the gong removed.

50 Fig. 3 is a cross-section along line 3—3 of Fig. 2.

Fig. 4 is a side elevation of my alarm device showing the tripping mechanism when in position for actuation by a door hinged on the left 55 side.

Fig. 5 is a fragmental view showing the tripping mechanism in position for actuation when the device is installed for actuation by a door hinged on the right side.

Fig. 6 is a perspective, non-assembled, detail view of the elements of the tripping mechanism.

Fig. 7 is a fragmental, detail view, partly in section, showing the tripping mechanism when set for trigger release of the sound-producing mechanism.

Fig. 8 is a fragmental view, partly in section, showing the special nut about which the swinging member is permitted to turn independently of the rest of the tripping mechanism.

Fig. 9 is a fragmental, detail view showing the connection between the rocking member and swinging member of my alarm device.

The alarm device comprises the octagonal casting 2 having the base 4, on which is secured the bracket 6, which in turn supports the gong 8 fastened thereto by the nut and bolt construction 10. If desired, casings of other configurations may be provided to meet the particular needs and fancy of the user. Extending upwardly through the base 4 is a spindle 12 to which is fastened one end of a coiled ribbon spring 14, the other end of the spring being fastened to a plate 16, which also is fixed to the base 4. A plate 18, in spaced relation to plate 16 and provided with teeth 20 at its periphery, is secured to the spindle 12 and rotates therewith. These teeth 20 mesh with the pinion 22 disposed on the shaft 24. This shaft 24 also carries the escapement or star wheel 26 which engages with the pallets 28 and 30 of the pendulum 32 pivoted on the stud 34 which is journaled in the sleeve 36 secured to the base 4. This dog or pendulum 32 has a clapper 38 at one end which produces an alarm-giving sound when it strikes the gong 8.

The plate 18 is provided with a plurality of upwardly projecting lugs 40, preferably integral therewith, which are disposed at a sufficient radial distance from the spindle 12 that movement in their path of rotation about the axis of this spindle will cause these lugs to engage the inner end 42 of the plunger or rocker arm 44 of the tripping mechanism when this rocker arm is pushed into its innermost position. This rocker arm 44 is disposed between the inner flange 46 of the casing 2 and a guide strap 48 secured to the flange 46. A portion 45 of this rocker arm 44 is of reduced cross-section and the guide strap is shaped to permit the rocker arm to turn therein at its reduced sectional portion. This reduced 55

portion is of greater length than the width of the guide strap 48, thereby permitting axial as well as circumferential movement of the rocker arm between the guide strap 48 and the flange 46. 5 The portion of the rocker arm projecting from the casing 2 and beyond the guide strap 48 is formed into a double bend providing a crank, the intermediate section 50 being perpendicular or nearly so to the part which is in rocking position 10 between the flange 46 and guide strap 48 and the end section 52 being perpendicular or nearly so to the section 50 and perpendicular or nearly so to the rocking portion between the flange 46 and the guide strap 48. The section 52 has a threaded 15 cavity or a threaded bore 54 to receive the end of a nut 56. This nut is provided with a non-threaded portion 58 of greater cross-sectional area than the threaded portion, but of smaller cross-sectional area than the head 60 of the 20 nut. An arm 62, hereinafter referred to as the swinging arm, is provided with a plurality of intersecting slots 64 of a size to receive the enlarged portion 58 of the nut 56. By this means the effective arm length of the arm 62 may be increased 25 or decreased, as desired. The thickness of the enlarged portion 58 of the nut is greater than the thickness of the swinging arm 62 thereby affording clearance so that, when this swinging arm 62 is disposed between the head 60 of the 30 nut and the section 52 of the rocker arm and the nut is tightened, the swinging arm 62 will be free to rotate about the enlarged portion 58 of the nut 56 independently of the rocker arm 44. This swinging arm 62 is bent so that the section 35 66, which is fastened on the nut 56, is perpendicular or nearly so to the section 68. This section 68 terminates in a knob 70, which is preferably covered with rubber or other suitable material, to serve the particular purpose set forth in the foregoing description. 40

A spring 72 and a retaining member or keeper 74 are fastened to the casing 2 and are located close to where the rocker arm 44 projects through the casing 2. The spring 72 bears against the 45 section 50 of the rocker arm 44 and urges this rocker arm in an outward direction from the casing. By forcing the section 50 against the tension of the spring 72 and also turning the rocker arm 44, the section 52 of the rocker arm 50 can be swung into a position between the keeper 74 and casing 2 and the rocker arm will be held locked so that the end 42 of this rocker arm or plunger 44 will be in the path of rotation of the lugs 40 on the plate 18 and will prevent or arrest 55 rotation of this plate 18 and the gear assembly connected therewith. The arm 62 will be in the extended position, as shown in Figs. 4 and 5, and the knob 70 will be disposed so that pressure on the end of this knob will exert a turning movement of the rocking arm 44. Therefore by bearing against the knob 70, the rocker arm 44 will be released from this locked condition, the section 60 52 of the rocker arm will be eased away from the keeper 74, and the spring 72 will push the rocker arm 44 in an outward direction from the casing 2, thereby drawing the end 42 of the rocker arm 44 away from the path of rotation of the lugs 40 on the plate 18, and ceasing to prevent or arrest 65 rotation of this plate 18 and the gear assembly connected therewith. 70

In using my device as a warning means should a burglar or other intruder seek to gain entrance to a room or other enclosure, the device is attached, as shown in Fig. 1, on the door jamb 76 75 adjacent to the door 78, the rocker arm 44 pushed

inwardly against the tension of the spring 72 and locked by the keeper 74, and the arm 62 swung so that the knob 70 of this swinging arm 62 will extend into the path of the door 78 when the latter is opened. 5

The coiled ribbon spring 14 having been wound with a suitable key by turning the stem 80 of the spindle 12, the tendency of the spring to uncoil will exert a force upon the gear assembly connected with the plate 18 to effect rotation of the members of this gear assembly. This rotation is prevented if any lug 40 on the plate 18 is kept from rotating when the rocker arm is pushed inward, as in the locked position heretofore described. 10

When the door 78 is opened a predetermined amount, it will bear against the knob 70, causing the swinging arm 62 to move the rocker arm 44 out of its locked position and away from the keeper 74. The spring 72 bearing against the section 50 of the rocker arm 44 will slide this rocker arm from the inner position in the casing 2, thereby releasing the lug 40 and bringing the inner end 42 out of the path of rotation of the lugs 40 on the plate 18. The plate 18 will now be 20 free to be rotated by the coiled spring 14 and will transmit its rotary motion through the gear assembly to the star wheel 26. This star wheel, alternately engaging the pallets 28 and 30 of the dog or pendulum 32 in the manner of the well 25 known clock escapement movements, will effect a vibration of the clapper 38, causing the latter to strike the gong 8 and producing ringing sounds. These ringing sounds will notify that someone has 30 entered through the door, while the alarm is set. Unless previously relocked against movement, the ringing will continue until the spring 14 unwinds to a point where it will no longer operate the gear assembly. 35

By rubber-coating the knob 70, a better and 40 surer grip is obtained when the door 78 engages the knob to actuate the tripping mechanism of the alarm. The rubber coating also prevents damage to the door from its contact with the 45 knob.

Installations as heretofore described have 50 proven very effective where it is not necessary to open the door from the outside after the alarm has been set for actuation by such door. However, such an alarm will be set off by a non-intruding person opening the door from the outside as well as by an intruder against whose entry the alarm has been provided. This causes objectionable noise, confusion and alarm at a time 55 when there is no desire for such an occurrence and annoyance. I will now describe my very novel and simple means for overcoming these disadvantages. 70

By inserting the enlarged portion 58 of the nut 56 in the proper slot of the series of intersecting slots 64, the swinging arm 62 is adjusted to permit the door to open a sufficient amount to allow a person acquainted with and aware of this construction to insert the hand through such limited opening and grasp the end 82 of the cord 84 passing through the guiding screw-eyes 86 and attached at 87 to the section 68 of the swinging arm 62. The end 82 may have a loop, ball or other suitable handle. By pulling on the end 82, the arm 62 will be swung out of the path of the moving door and the alarm mechanism will not be actuated when the door opens. When it is desired to set this alarm device on leaving by this door, the door is opened to a point permitting the person to pass through and the arm 62 is swung 75

so that the knob 70 will contact with the door. Then as the door closes, after the person has passed through, the swinging arm will fall to a position where it will be set for actuation by the door to release the tripping mechanism when the door is again opened a sufficient amount, unless before the door has opened sufficiently to actuate this tripping mechanism the swinging arm is, by means of the string 84, swung into position where 10 the knob 70 will not be in the path of the opening door.

In order to limit the downward movement of the swinging arm 62 and to provide a position where it will be set to be effectually operated by 15 the opening door, I have provided a stop 88.

When my device is to be used with a door hinged on the right side, the stop 88 is adjusted to assume the position shown in Fig. 5, and the string 84 will be guided through an eyelet 90, 20 located on the opposite side of the tripping mechanism from that of the eyelet 86.

Another novel feature of my invention resides in the unique adaptation of the alarm to window shades or blinds. When so used, a cord or string 25 92 is attached at one end to section 50 or section 52, of the rocker arm 44 at one of the openings 93, passes through several eyelets 94 and is attached at the other end to a hook or other stationary terminal 96. The shades 98 of the 30 windows are drawn down and a weight 100 is hung from each shade by suitable means such as a hook 102 passing through the cord ring 104 of the shades. These hooks are also preferably provided with eyes 106 through which the string 35 92 is passed before its attachment to the support 96. Should an intruder try to enter through a window equipped with my alarm, as above described, any raising or other movement of the shade 98 will cause an upward pull on the part 40 of the string 92 below, such shade thereby sounding the alarm. If, however, the shade is lowered or the shade or the string 108 of the shade is severed, allowing the weight 100 to fall, there will also be a downward pull on the part of the 45 cord or string 92 below the shade, thus sounding the alarm. It is to be understood that the weight 100 is light enough to be adequately supported by the window shade spring, but heavy enough to actuate the tripping mechanism, when the full 50 weight thereof bears on the cord 92.

My device also finds suitable application as a robber alarm for stores, banks, pay roll offices, etc. When so used, a string 110 is led from the rocker arm 44, as in the case of the alarm protection used with window shades, and this string is passed through suitable guiding eyelets 112 so it will pass close to the floor under a counter 113 or other suitable place where it will be in position for ready actuation by the foot when the alarm is 60 to be given. The end of this string is connected to a suitable terminal 114.

When my device is to be employed as a fire alarm, the keeper 74 is preferably made of two substantially L-shaped members 116 and 118, as 65 shown in Fig. 7. These two members 116 and 118 are held together by an alloy or other suitable material 120 of proper low-melting point, for example, a metal or wax composition melting at about 120° F. This alloy or other composition 70 may be fused to the two members or else may be inserted as a plug in openings in the members 116 and 118. With the alarm mechanism wound to give an alarm, and the rocker arm 44 in locked position, when the temperature of the air surrounding this fire alarm becomes sufficiently high 75

to melt this composition, the member 118 will slide away from the member 116, thereby releasing the rocker arm and permitting the alarming mechanism to function.

My device may be employed either with or without the thermostatically controlled mechanism. In the latter case, however, it will not function as a fire alarm.

My invention can be employed for either burglar, robber or fire alarm or for two or more of these purposes. Separate alarm mechanisms, constructed as heretofore described, may be employed for each purpose and also for each window and door. However, my device also lends itself to installations wherein a single alarm mechanism can be made to serve simultaneously for protection against intruders through a door as well as through one or more windows, protection against robbery and also protection against fire.

The device can be readily and manually set for use. It can be either fixed or removably attached to any part of a room or other convenient structure. It can also be set for a series of rooms or enclosures.

My device is independent of any source of electric energy and therefore is not exposed to being put out of operation through the destruction of the source of electric energy or interruption in the path of the electric current. It will also be noted that, with my alarm device, the strings or cords connected with the tripping mechanism are not under tension when the mechanism is set and the alarm is not giving sound warning. These strings or cords may be of fabric or metal, and in some installations may be replaced in whole or in part by wire. The screw eyelets for guiding the strings or cords should be provided in sufficient number and at suitable locations to properly support these strings or cords, and to prevent tangling or other interference between the cords when two or more cords are employed in close proximity to each other. Instead of using screw eyelets for guiding the strings or cords, other means, such as pulleys, staples, etc., may be substituted in whole or in part for these screw eyelets.

It is to be understood that in employing my device as a fire alarm, instead of having the keeper 74 made of two members held together by a fusible composition, the fusible material may constitute some other suitable part of the mechanism so that the rocker arm 44 would be released when the fusible composition melts.

The present invention is not limited to the specific details set forth in the foregoing examples which should be construed as illustrative and not 55 by way of limitation, and in view of the numerous modifications which may be effected therein without departing from the spirit and scope of this invention, it is desired that only such limitations be imposed as are indicated in the appended 60 claims.

I claim as my invention:

1. An alarm comprising a gong, a clapper, spring motor means for operating said clapper, means for winding said spring motor, means for arresting operation by said spring motor means, said arresting means comprising an elongated, slidably-mounted, rocking member disposed to turn on an axis extending lengthwise of said rocking member and to move along an axis extending lengthwise of said rocking member and having a crank arm, a keeper for holding said crank arm and thereby locking said rocking arm in arresting position, a swinging member connected to said crank arm and disposed to turn 70 75

said crank arm from its engagement with said keeper, and resilient means acting on said crank arm for sliding said rocking member away from engagement with said spring motor means when 5 said crank arm is disengaged from said keeper.

2. An alarm comprising a gong, a clapper, spring motor means for operating said clapper, means for winding said spring motor, a stop on said clapper-operating means, means for arresting operation of said clapper by said spring motor means, said arresting means comprising an elongated, slidably-mounted, rocking member having a crank arm and disposed to turn on an axis extending lengthwise of said rocking member, to 10 move along an axis extending lengthwise of said rocking member and to engage said stop, a keeper for holding said crank arm and thereby locking said rocking member in arresting position, a swinging member connected to said crank arm 15 and disposed to turn said crank arm from its engagement with said keeper, resilient means acting on said crank arm for sliding said rocking member away from the path of movement of said stop when said crank arm is disengaged from said 20 keeper, and means for connecting said rocking and said swinging members and allowing said swinging member to turn about said connecting means independently of said rocking member.

3. An alarm comprising a gong, a clapper, 30 spring motor means for operating said clapper, means for winding said spring motor, a stop on said clapper-operating means, an elongated slidably-mounted rocking member disposed to turn on an axis extending lengthwise of said rocking 35 member, to move along an axis extending lengthwise of said rocking member and to engage said stop, a keeper for locking said rocking member in engagement with said stop, a swinging member adapted to unlock said rocking member, 40 resilient means acting on said rocking member for separating said rocking member from the path of movement of said stop when said rocking member is unlocked, means for connecting said rocking and said swinging members and allowing said 45 swinging member to turn about said connecting means independently of said rocking member, said swinging member having means whereby the position of the connecting means relative to the swinging member may be varied and regulated.

4. A burglar alarm device adapted for use adjacent to a door and actuation by opening said door, said alarm comprising a gong, a clapper, spring motor means for operating said clapper, means for winding said spring motor, means for arresting operation of said clapper by said spring motor means, said arresting means comprising an elongated, slidably-mounted, rocking member disposed to turn on an axis extending lengthwise 50 of said rocking member and to move along an axis extending lengthwise of said rocking member and having a crank arm, a keeper for holding said crank arm and thereby locking said rocking arm in arresting position, a swinging member connected to said crank arm, projecting into the path of the door when said door is 55 opening and disposed to turn said crank arm from its engagement with said keeper.

5. A burglar alarm device adapted for use adjacent to a door and actuation by opening said door, said alarm comprising a gong, a clapper, spring motor means for operating said clapper, means for winding said spring motor, means for arresting operation by said spring motor means, 70 means actuated by the opening of the door for

releasing said arresting means, said arresting means comprising an elongated slidably-mounted rocking member disposed to turn on an axis extending lengthwise of said rocking member and a keeper for locking said rocking member in arresting position and said releasing means comprising a movable member projecting into the path of the door when said door is opening and having connection with and adapted to unlock said rocking member, and means for regulating and adjusting the extent of projection of said movable member into the path of the door when said door is opening and thereby determine how far said door will be permitted to open without actuating said releasing means. 5

6. A burglar alarm device adapted for use adjacent to a door and actuation by opening said door, said alarm comprising a gong, a clapper, 20 spring motor means for operating said clapper, means for winding said spring motor, means for arresting operation by said spring motor means, means actuated by the opening of the door for releasing said arresting means, said arresting means comprising an elongated slidably-mounted rocking member disposed to turn on an axis extending lengthwise of said rocking member and to move along an axis extending lengthwise of said 25 rocking member and a keeper for locking said rocking member in arresting position, and said releasing means comprising a movable member projecting into the path of the door when said door is opening and having connection with and adapted to unlock said rocking member, means for regulating and adjusting the extent of projection of said movable member into the path of the door when said door is opening and thereby determine how far said door will be permitted 30 to open without actuating said releasing means, and means in engagement with said movable member for shifting said movable member out of projection into the path of the door when the door is opening. 35

7. A burglar alarm device adapted for use adjacent to a door and actuation by opening said door, said alarm comprising a gong, a clapper, spring motor means for operating said clapper, means for winding said spring motor, a stop on said clapper-operating means, an elongated slidably-mounted rocking member disposed to turn on an axis extending lengthwise of said rocking member, to move along an axis extending lengthwise of said rocking member and to engage said stop, a keeper for locking said rocking member in engagement with said stop, a swinging member projecting into the path of the door when said door is opening and having connection with and adapted to unlock said rocking member, means for regulating and adjusting the extent of projection of said swinging member into the path of the door when said door is opening and thereby determine how far said door will be permitted to open without actuating said swinging member, means in engagement with said swinging member for shifting said swinging member out of projection into the path of the door when the door is opening, and resilient means acting on said rocking member for separating said rocking member from the path of movement of said stop when said rocking member is unlocked. 45

8. A burglar alarm device adapted for use adjacent to a door and actuation by opening said door, said alarm comprising a gong, a clapper, spring motor means for operating said clapper, 50

- means for winding said spring motor, a stop on said clapper-operating means, an elongated slidably-mounted rocking member disposed to turn on an axis extending lengthwise of said rocking member, to move along an axis extending lengthwise of said rocking member and to engage said stop, a keeper for locking said rocking member in engagement with said stop, a swinging member projecting into the path of the door when said door is opening and adapted to unlock said rocking member, means for regulating and adjusting the extent of projection of said swinging member into the path of the door when said door is opening and thereby determine how far said door will be permitted to open without actuating said swinging member, means in engagement with said swinging member for shifting said swinging member out of projection into the path of the door when the door is opening, resilient means acting on said rocking member for separating said rocking member from the path of movement of said stop when said rocking member is unlocked, and means for connecting said rocking and said swinging members and allowing said swinging member to turn about said connecting means independently of said rocking member.
9. An alarm comprising a gong, a clapper, spring motor means for operating said clapper, means for winding said spring motor, a stop on said clapper-operating means, means for arresting operation of said clapper by said spring motor means, said arresting means comprising an elongated, slidably-mounted, rocking member having a crank arm and disposed to turn on an axis extending lengthwise of said rocking member, to move along an axis extending lengthwise of said rocking member and to engage said stop, a keeper for holding said crank arm and thereby locking said crank arm in arresting position, a swinging member connected to said crank arm and disposed to turn said crank arm from its engagement with said keeper, and resilient means acting on said crank arm for sliding said rocking member away from the path of movement of said stop when said crank arm is disengaged from said keeper, said keeper containing fusible material adapted to release said rocking member from the locked position when the air about said alarm attains a predetermined temperature.
10. An alarm comprising a gong, a clapper, spring motor means for operating said clapper, means for winding said spring motor, said clapper-operating means including a toothed plate having a stop thereon, means for arresting operation of said clapper by said spring motor means, said arresting means comprising an elongated, slidably-mounted, rocking member having a crank arm and disposed to turn on an axis ex-
- tending lengthwise of said rocking member, to move along an axis extending lengthwise of said rocking member and to engage said stop, a keeper for holding said crank arm and thereby locking said crank arm in arresting position, resilient means acting on said crank arm for sliding said rocking member away from the path of movement of said stop when said crank arm is disengaged from said keeper, and a cord extending from said crank arm and disposed to unlock said rocking member when a pull is exerted on said cord.
11. An alarm installation comprising a gong, a clapper, spring motor means for operating said clapper, means for winding said spring motor, a stop on said clapper-operating means, an elongated slidably-mounted rocking member disposed to turn on an axis extending lengthwise of said rocking member, to move along an axis extending lengthwise of said rocking member and to engage said stop, a keeper for locking said rocking member in engagement with said stop, a cord extending from said rocking member and passing under a window, a weight connected with said cord and supported above said cord by the window shade of said window, said cord being disposed to unlock said rocking member when a pull is exerted on said cord, and resilient means acting on said rocking member for separating said rocking member from the path of movement of said stop when said rocking member is unlocked.
12. A burglar alarm device adapted for use adjacent to a door and actuation by opening said door, said alarm comprising a gong, a clapper, spring motor means for operating said clapper, means for winding said spring motor, means for arresting operation of said clapper by said spring motor means, said arresting means comprising an elongated, slidably-mounted, rocking member disposed to turn on an axis extending lengthwise of said rocking member and to move along an axis extending lengthwise of said rocking member and having a crank arm, a keeper for holding said crank arm and thereby locking said crank arm in arresting position, a swinging member connected to said crank arm, projecting into the path of the door when said door is opening and disposed to turn said crank arm from its engagement with said keeper and to swing easily and without resistance to further opening of said door after disengagement of said crank arm from said keeper by pressure of said opening door on said swinging member, and resilient means acting on said crank arm for sliding said rocking member away from the path of movement of said stop when said crank arm is disengaged from said keeper.

NATHAN M. LEVY.
